UNITED STATES PATENT OFFICE.

EDDY R. WHITNEY, OF PHILADELPHIA, PENNSYLVANIA, ASSIGNOR TO COMMERCIAL TRUCK COMPANY OF AMERICA, OF PHILADELPHIA, PENNSYLVANIA, A CORPORATION OF PENNSYLVANIA.

TOWER-WAGON.

1,096,656.

Specification of Letters Patent.

Patented May 12, 1914.

Application filed August 27, 1912. Serial No. 717,264.

To all whom it may concern:

Be it known that I, EDDY R. WHITNEY, a citizen of the United States, residing in Philadelphia, Pennsylvania, have invented 5 an Improved Tower-Wagon, of which the following is a specification.

One object of my invention is to provide a tower wagon of the type employed for trimming arc lamps, with a novel means for 10 mechanically raising and lowering its platform; it being particularly desired that the construction, while being relatively light and conveniently operative, shall be substantial, shall consist of but relatively few parts, 15 and shall not be likely to get out of order or require repair.

Another object of my invention is to provide a tower elevating mechanism including 20 a motor-actuated screw, so mounted that under operating conditions it shall be in tension, while the apparatus as a whole shall be so placed as to be relatively near the center of gravity of the structure to which it is applied, although to one side of the 25 center line thereof.

I also desire to provide a motor-actuated tower elevating mechanism with novel 30 means for controlling its operation, either from the platform or from the body of the structure on which it is mounted; the arrangement of parts being such as to permit of the convenient control of the motor regardless of the position of the adjustable 35 platform-carrying structure.

These objects and other advantageous 40 ends I secure as hereinafter set forth, reference being had to the accompanying drawings, in which—

Figure 1, is a side elevation of a tower wagon constructed according to my invention and showing the platform-carrying structure in its elevated position; Fig. 2, is a side elevation on an enlarged scale illustrating the detail construction of the upper 45 part of the tower and showing the platform-carrying structure in its lowered position; Figs. 3, 4, 5 and 6 are horizontal sections taken respectively on the lines *a—a*, *b—b*, *c—c*, and *d—d*, Fig. 2, the latter section being inverted; Fig. 7 is a vertical section on an enlarged scale taken on the line *f—f*, Fig. 5; Figs. 8 and 9 are horizontal sections taken on the lines *g—g* and *h—h*, Fig. 7; Fig. 10, is an inverted plan of the motor controlling switch; Fig. 11, is a vertical sec-

tion on the line *e—e*, Fig. 10, and, Fig. 12 is a vertical section illustrating the detail construction of the screw suspending device preferably employed as part of my invention.

In the above drawings, 1 represents the body of my improved tower wagon which is provided with a lower driver's seat 2, and is mounted on two pairs of wheels 3 and 4. Through any suitable mechanism (not shown) this wagon is driven from an electric motor 5, receiving current from a storage battery located in a box 6 mounted under the body 1. On said body and preferably over the rear pair of wheels 4, is mounted the fixed portion 7 of the tower structure which consists of four rolled sections 7^a, properly fixed to said wagon body and trussed or braced together in any suitable manner so as to outline an open, upwardly tapering frame on one side of which, adjacent the top thereof, is fixed an elevated driver's seat 8.

The controller 9 for governing the operation of the motor 5 is mounted on the foot board 10 of said elevated seat and by means of mechanism forming no part of the present invention, may be operated either from this seat or from the lower driver's seat 2. The steering mechanism of the vehicle is 85 likewise controllable from either of the two seats through steering wheels 11 and 12, while the brake mechanism is operative by means of foot levers 13 and 14 properly situated relatively to the seats 8 and 2 respectively, 90 there also being a hand lever 15, whereby the brakes may also be set or released. This mechanism is fully described and claimed in an application for U. S. patent, filed jointly by me and by Emlen S. Hare on May 2nd, 95 1911, Serial No. 624,587.

As shown in Fig. 4, within the upper part of the fixed tower structure 7 are mounted four vertically placed angle sections 16 forming guideways, and, in the present instance, these are so arranged as to define a substantially square prism, being supported by and rigidly fixed to the tower structure 7 so as to be substantially central thereof by bracing members 17 and 18.

Vertically slidable within the guide-way provided by the angle sections 16 is the vertically movable part 19 formed of four angle sections 19^a, latticed or otherwise suitably braced together so as to outline an elong-

gated figure of square section. On the upper end of this movable structure is mounted a platform 20 which may be rotatable on a vertical axis in the manner well understood 5 in this art; there being, in the present instance, a bearing ring 21 fixed to the top of the movable structure 19 and engaged by a second bearing ring 22, fixed to the platform which is held in place by hooks 23 extending 10 under said ring 21.

For raising and lowering the movable tower structure 19, I provide an electric motor 24 of suitable power, mounted in the lower part of the fixed tower structure 7 15 from which it is supported by suitable members 26 and 25, as shown in Figs. 1 and 6. Said motor is preferably so mounted that the line of its armature shaft is to one side of the central line of the tower structure and 20 said shaft is operatively connected to an elongated screw 27 hung from the upper part of the fixed tower structure, and engages a nut fixed to the movable structure 19 of said tower. For suspending said 25 screw, I preferably provide the construction shown in Fig. 12, which includes a transverse member 28 in the form of a structural section rigidly fixed to one side of the top of the fixed tower structure 7. Movably 30 carried by this member is a hollow head in the form of a cup like casting 29 having a removable cap 30 and internally provided with anti-friction bearings 31 on which rests a flanged collar 32. The screw 27 extends 35 into the bottom of the socket casting 29 and is threaded into a collar 32, to which it is rigidly held by means of a jam nut 33. The exterior contour of the casting 29 is such that it fits into the spherically curved socket 40 recess in the member 28, thus making it possible for it with the screw to change its position in order to adjust itself to variations in the relative positions of its supporting structure and the motor 24 without causing 45 objectionable strains. A retaining collar 34 is preferably fixed to the neck portion of the head 29 which extends through the member 28, so as to prevent its accidental displacement.

50 The lower end of the screw is coupled to the armature shaft of the motor 24 through some form of clutch or frictional connecting device such, for example, as that shown in detail in Figs. 7, 8 and 9. This device consists of a square dog 35 keyed or otherwise rigidly fixed to the end of the shaft 36 and fitting into a correspondingly shaped opening in the yoke piece 37 to form a slip joint for driving the same while permitting a limited 55 vertical movement between the motor and the screw. The upper end 38 of the yoke is formed with upper and under bearing surfaces and has a circular hole through which passes the square end 39 of the screw 60 65 27. The lower end of said screw is pro-

vided with a removable head 40 and it also has an annular shoulder 41 a short distance above the upper end 38 of the yoke 37. Between said shoulder and said yoke I mount a metallic washer 42 and a leather or fiber washer 43, the latter being in contact with the upper bearing surface of the yoke. A second leather or fiber washer 44 is in engagement with the under bearing surface of the yoke, toward which it is pressed by a spring 45 confined between the head 40 and a second metallic washer 46.

The screw 27 is operatively connected to the movable part 7 of the tower structure through a nut 47 which consists of an elongated cylindrical casting containing a body of Babbitt or other bearing metal 48 formed with a hole through it threaded for the reception of said screw. Said nut is provided with a pair of oppositely disposed trunnions 49 for the reception of the two arms of the forked end of an equalizing member 50 whose opposite end is in the form of a spindle 51 rotatably fitting into a suitable bearing in that side of the movable tower structure 19 opposite that to which the screw 27 is adjacent. In order that the upward thrust of the nut shall be equally divided between the two opposite sides of said structure 19, the member 50 is connected to that side thereof adjacent the screw, by means of a bolt 52 whose head has a spherically curved portion 53 fitting into a correspondingly formed socket or recess in the upper face of said member 50. The lower end of the bolt has a nut and a second spherically curved bearing piece 55 fitting into a correspondingly formed recess in the under face of a bar or plate 56 fastened to and forming part of the movable tower structure 19. As a result of the use of this equalizing member 50, the raising force is applied to the movable part 7 of the tower structure in such a manner that this latter does not tend to jam in its guide ways or tilt materially from a vertical position. By reason of the particular design of this member as shown in detail in Fig. 7, the tendency of the movable tower structure to fall over toward the upper part of the screw 27 is equalized by the downward force exerted by the end 51 of the equalizing bar, which, because of its peculiar mounting, is free to adjust itself to suit any side strains which may be set up in the tower structure by reason of a weight 100 at any part of the platform 20.

For controlling the operation of the motor 24, I provide a suitable switch 57, which, while it may be of any suitable construction, preferably includes a rotatable member 58 carrying contacts and in the present instance keyed or otherwise fixed to a shaft 59 of square section extending centrally of the fixed and movable tower structures. The lower end of said shaft, below the switch 27, 115 120 125 130

has fixed to it an operating handle 60, and in order that it may be manipulated from the platform 20, I mount on the latter a downwardly extending tube 61 of square 5 interior section, designed to receive within it the shaft 59 and to telescope with the same. This tube 61 is rotatably carried by said platform so as not to interfere with the rotation thereof and is provided with an 10 operating handle 62, whereby it and therefore the shaft 59, may be rotated to actuate the switch 57. The movable switch member 58 is provided with a suitably toothed ratchet 63 indicated in dotted lines in Fig. 15 10, and a coöperating pawl 64, whereby it is removably held in its off position or in either of two operating positions corresponding to forward and reverse operation of the motor, as may be desired.

20 Under conditions of use the movable tower structure with its platform 20 may be raised by causing operation of the motor 24 through the agency of the switch 37, which may be actuated from the body 1 of the 25 vehicle by means of the handle 60, or from the platform 20 by the handle 62. In any case the telescopic parts 59 and 61 maintain an operative connection between the handle 62 on the platform and the movable switch 30 member 58, so that a person on the platform can conveniently govern its position.

When the motor armature is turned, power is transmitted from the shaft 36 to the yoke 37, and by reason of the frictional engagement of the upper and lower bearing surfaces of its end 38 with the washers 43 and 44, the screw 47 likewise is turned. Should the latter jam for any reason, or turn with such difficulty as to impose an abnormal load 40 on the motor 24, the clutch provided by the yoke 37 and the washers 43 and 44, would slip, since the spring 45 would yield sufficiently to permit such action under predetermined abnormal conditions. Of course, 45 when the load is again returned to its normal amount, power is transmitted through said clutch and drives the screw as desired.

Obviously, the rotation of the screw 47 in the proper direction, through the medium of 50 the nut 27 and the equalizing member 50, causes an upward movement of the movable tower structure 19 with its platform, while a reverse operation of the motor, as determined by the manipulation of the switch 57, 55 would cause lowering of the said parts. The possibility of injurious lateral strains being put on the screw or its associated parts, is reduced to a minimum owing to the ball and socket connections between the upper end of 60 said screw and the beam 28 by which it is connected to the fixed tower structure, and also to the trunnion connection between the equalizing bar 50 and the nut 47, as well as to the universal connection between the said 65 bar and the said movable tower structure.

It is to be noted that since the screw is hung by its upper end from the fixed tower structure it is not only in tension under operating conditions, but its weight is carried independently of the motor which is supported adjacent the bottom of said fixed tower structure. 70

I claim:

1. The combination of a fixed tower structure; a movable tower structure telescoping therewith; and means for raising and lowering said movable tower structure on the fixed structure, the same including a motor, a screw driven thereby and mounted to one side of the center line of said tower structures; with means for maintaining said screw in tension under operating conditions. 80

2. The combination of a fixed tower structure; a movable tower structure; and means for raising and lowering said movable tower structure, the same including a screw hung from the upper part of the fixed tower structure and operatively connected to the movable tower structure; with a motor for driving said screw. 85

3. The combination of a fixed tower structure; a movable tower structure; and means for raising and lowering said movable tower structure; the same including a screw adjustably connected to the upper part of the fixed tower structure and operatively connected to the movable tower structure; with a motor for driving the screw. 90

4. The combination of a two part tower structure; and means for raising and lowering one of the parts of said structure relatively to the other, the same consisting of a motor; a screw driven therefrom and independently carried on one of the tower parts, the screw being hung from its upper end; and means for operatively connecting said screw to the second tower part. 100

5. The combination of a two part tower structure; and means for raising and lowering one of the tower parts relatively to the other; the same consisting of a motor and a screw connected to said motor and suspended from one of the tower parts; frictional connecting means between said screw and the motor; and a nut carried by the movable tower part in engagement with the screw. 110

6. The combination of a two part tower structure made in two telescoping parts; a screw mounted on one of the tower parts, and extending in a line parallel to the line of movement of the other part; a motor for actuating the screw; and means for connecting the screw to the other tower part consisting of a nut operative on said screw; with a member movably connected to said second tower part and trunnioned to the nut. 120

7. The combination of a two part tower structure; and means for raising and lowering one part of said structure relatively to the other, the same consisting of an equaliz- 130

ing bar mounted on one part of the tower structure; a nut carried by said equalizing bar; a screw carried on the other part of the tower structure to one side of the center line thereof and in engagement with said nut; and a motor for driving the screw.

8. The combination of a two part tower structure; and means for raising and lowering one part of the tower structure relatively to the other, the same consisting of a screw; a ball and socket joint for suspending said screw from the top of one part of the tower structure; a motor connected to the screw; a nut on the screw; with means for movably connecting said nut with the second part of the tower structure.

9. The combination of a two part tower structure; a motor and a screw independently mounted on one part of the tower structure; means for operatively coupling the motor and the screw including a slip joint for permitting a variation of the distance between said parts; and a nut operative on the screw and connected to the second part of the tower structure.

10. The combination of a two-part tower structure; and means for raising and lowering one part of the tower structure rela-

tively to the other, consisting of a motor-driven screw mounted to one side of the center line of the tower structure; a nut engaging said screw; an equalizing bar trunnioned to the nut and rotatably mounted on one part of the tower structure; with a tension member also connecting said bar to said part of the tower structure.

11. The combination of a two-part tower structure; and means for raising and lowering one part of the tower structure relatively to the other, the same consisting of a motor-driven screw mounted to one side of the center line of the tower structure; a nut engaging said screw; an equalizing bar trunnioned to the nut and rotatably mounted on one part of the tower structure; with a tension member also connecting said bar to said part of the tower structure and having a ball and socket attachment thereto.

In testimony whereof, I have signed my name to this specification, in the presence of 50 two subscribing witnesses.

EDDY R. WHITNEY.
